ATTORNEY

UNITED STATES PATENT OFFICE

ARTHUR D. LUND, OF MINNEAPOLIS, MINNESOTA, ASSIGNOR TO ALCET ELECTRO-PRODUCTS CORPORATION, OF NEW YORK, N. Y., A CORPORATION OF DELAWARE

MOLD TREATING MECHANISM FOR GRID CASTING MACHINES

Original application filed August 24, 1928, Serial No. 301,830. Divided and this application filed August 17, 1929. Serial No. 386,554.

This invention relates to mold treating mechanisms for casting machines, and the primary object is to provide an efficient, practical, and comparatively simple device for coating the mold faces so that the casting metal will not adhere thereto. More specifically the object is to provide a transversely shiftable burner unit that is carried on a track or rail, for manual manipulation, and which is so designed that it can quickly and properly be moved through between the mold faces, while the molds are open and after they have discharged a previously made casting. The present application is a division of my co-pending application, Ser. No. 301,830, filed August 24, 1928, for grid casting machine, and reference is made to that application for a more complete understanding of the application of the treating mechanism to the casting machine as a whole.

In the accompanying drawings:

Fig. 1 is a plan or top view of the mold treating mechanism, fractional portions being broken away.

Fig. 2 is an end elevation of the device, partly in section, as on the line 2-2 in Fig. 1.

Fig. 3 is a detail section, as on the line 3-3 in Fig. 1, but showing the burner carriage as shifted to and locked in its idle position.

Referring to the drawings more particularly and by reference characters, A and B designate a pair of separable casting molds. The mountings and actuating mechanisms for these molds are omitted, as they form no part of the present invention and are fully disclosed in the above mentioned application, Ser. No. 301,830, it being sufficient to state that the molds are brought together when to receive the molten metal and are separated to discharge the finished castings. Before the molds are again closed, to receive metal for the next casting to be formed, the treating process is applied, although it may be explained that in some instances the treatment need only be applied once for two or several casting operations.

The numeral 4 designates a rectangular frame that is suitably secured to some rigid part of the machine near the molds A and B.

Upon the vertical end bars of the frame 4 I mount two bracket arms 5 which support a transversely extending guide bar or track 6. Upon this bar is slidably mounted a casting 7 through which extends and from which depends a burner tube 8 having two opposite rows of burner tips 9. The pipe or tube 8 has a valve 10, and connects with a flexible hose 11 that supplies gas to the burner 8 when the valve 10 is open. A pilot tube 12 connects with the gas supply, in advance of the valve 10, and has a burner tip 13, adjacent the lower end of the burner pipe 8, which, when once lit, will light the burner 8 each time the valve 10 is opened. When the lower burner tips 9 are thus ignited the flame immediately passes or runs up the pipe, lighting the other tips. The valve 10 is opened and closed by turning a hand rod 14, pivotally secured to the bore extension bolt 15 of the valve. The bolt 15 is further provided with a finger 16, adapted to drop or swing into a notch 17, in the bar 6, when the carrier 7 is in the left hand position indicated by dotted lines in Fig. 1. When the finger 16 is in the notch 17 the valve 10 is closed and there is no gas flowing to the burner 8. In any other position of the finger 16, however, the gas supply to the burner is open and the latter is ignited.

During the interval of time in which the molds are open, an attendant, stationed at the right side of the machine, grasps, turns, and pulls the handle bar 14, thus opening the valve 10, lighting the burner 8, releasing the finger 16 of the carrier, and draws the burner 8 entirely through or across both sets of molds, causing the flames at the burner tips 9 to thoroughly and evenly treat or smoke all of the matrix surfaces. He repeats this treatment by pushing the carrier back to its original position.

The construction thus described not only serves to economize on the gas consumption, as it is a simple matter for the operator to turn the rod 14 which he already holds in his hand when a smoking operation is completed; but also serves as a warning signal to prevent damage that would be caused if the burner were clamped between the molds,

because if the operator has not pushed the carriage far enough over to permit the finger 16 to engage the notch 17, he cannot shut off the flame, and consequently knows that the carriage has not been moved far enough so that the burner 8 will engage the closing molds.

It is understood that suitable modifications may be made in the structure as disclosed, 10 provided such modifications come within the spirit and scope of the appended claims.

Having now therefore fully illustrated and described my invention what I claim to be new and desire to protect by Letters Patent 15 is:

1. In a casting machine having a pair of separable molds, a carriage movable longitudinally with respect to the faces of the molds, a burner and pilot mounted on the carriage, a valve for the burner, and means, 20 operative to prevent closing of the valve except when the carriage is in a predetermined position.

2. In a casting machine having a pair of separable molds, a burner normally resting in an idle position adjacent the ends of the molds, means for guiding the burner centrally through between the molds when the latter are separated, and means for moving 25 the burner between the molds, said means including a burner valve controlling device.

3. In a casting machine having a pair of separable molds, a burner normally disposed in an idle position adjacent the ends of the molds, means for guiding the burner through 30 between the molds when the latter are separated, and a handle pivotally connected to the burner for manually actuating it between the molds.

4. In a casting machine having a pair of separable molds, a burner normally disposed in an idle position adjacent the ends of the molds, means for guiding the burner through 35 between the molds when the latter are separated, a valve for the burner, and an actuator element for moving the burner and controlling the valve.

5. In a casting machine having a pair of separable molds, a burner normally disposed 40 in an idle position adjacent the ends of the molds, means for guiding the burner through between the molds when the latter are separated, a valve for the burner, and an actuator element for moving the burner and controlling the valve, said actuator element comprising a handle member pivotally connected to the burner.

6. A mold treating device for casting machines comprising a track, a carriage mounted 45 upon the track for guiding action thereon, and a burner and burner valve carried by the carriage.

7. A mold treating device for casting machines comprising a track, a carriage mounted 50 upon the track for guiding action thereon,

a burner and valve therefor carried by the carriage, and means operative to prevent closing of the valve except when the carriage is in a predetermined position on the track.

8. A mold treating device for casting machines comprising a track, a carriage mounted 55 upon the track for guiding action thereon, a burner carried by the carriage, a valve for the burner, means for controlling the valve, and means operative to prevent closing of the valve except when the carriage is in a predetermined position on the track.

9. A mold treating device for casting machines comprising a track, a carriage mounted 60 upon the track for guiding action thereon, a burner and valve therefor carried by the carriage, a closer for the valve, said track having a notch at a predetermined position therein, and said valve closer having a lug for engagement in the notch to permit closing 65 of the valve.

10. A mold treating device for casting machines, comprising a transversely movable carriage, a burner unit and a valve therefor carried by the carriage, and a manually operative control member for opening and closing 70 the valve and moving the carriage.

Signed at Minneapolis, in the county of Hennepin, and State of Minnesota, this 15th day of August 1929.

ARTHUR D. LUND.
